UNITED STATES PATENT OFFICE.

ANDREW J. HOLMES, OF TACOMA, WASHINGTON.

ELECTRIC HEATER.

1,384,113.

Specification of Letters Patent. Patented Sept. 20, 1921.

Application filed August 27, 1920. Serial No. 406,317.

To all whom it may concern:

Be it known that I, ANDREW J. HOLMES, a citizen of the United States, residing at Tacoma, in the county of Pierce and State of Washington, have invented a certain new and useful Improvement in Electric Heaters, of which the following is a specification.

My invention relates to improvements in electric heaters and the object of my invention is to provide a heater that is adapted for installation in the floor of a room to be heated and having suitable controlling mechanism to govern the heating of the same.

Another object of my invention is to provide an electric heater wherein the elements are so disposed as to insure a uniform heating of the entire volume of air during its passage through the heating system.

A further object is to provide an electric heater adapted to be connected with air conduits whereby air may be taken in and conducted through said heater together with the air within the room.

A still further object is to provide an electric heater wherein the air passing therethrough is heated and also moistened to maintain the proper humidity in the room.

A still further object is to provide an electric heater embodying simplicity and economy in its construction which is positive and efficient in its operation.

The invention consists in the novel construction, adaptation and combination of parts of an electric heater as will be more clearly hereinafter described and claimed.

In the accompanying drawings Figure 1 is a view in mid-vertical section of an electric heater constructed in accordance with this invention.

Fig. 2 is a plan view, partly broken away to show the details of my invention.

Fig. 3 is a view of a detail of my invention in vertical section substantially on a line 3, 3 of Fig. 1.

Fig. 4 is a view of a detail of my invention in vertical section substantially on a line 4, 4 of Fig. 2.

Referring to the drawings throughout in which like reference figures indicate like parts, the numeral 5 designates the floor of a room. 6 designates a wall of said room communicating with the exterior of the house.

7 is an air conduit communicating with the exterior, provided with a screen 8, and a register 9 provided with the usual shutters. 10 is an air conduit communicating with the

interior of the room, provided with the usual grille 11 and a register 12. 13 designates a rectangular grille for air intake 60 and 14 is a circular grille through which the heated air radiates, regulated by a register 15. 16 designates the heater housing, provided with an annular basin 17, substantially as shown in the drawings. Mounted 65 within said housing are heating coils 18, comprising electrical resistance wires 19 secured around porcelain tubes 20 and cores 21. Said coils are held in clamped position between an upper annular plate 22 and 70 lower plate 23 by the rods 24 substantially as shown. Said upper annular plate is secured to flanges 25 projecting downward from the grille 14 by suitable fastenings 26 as shown in Fig. 4.

The conical disposition of the heating coils within the housing is for the purpose of effecting a greater degree of efficiency in heating the air as it passes through the system. The cool air is deflected to the lower 80 part of the coils by the walls of the reservoir where it becomes heated, expands and rises in conformity with the divergence of the coils. This feature will tend to bring the air in constant contact with said coils during its 85 expansion and upward passage through the heater. The coils may be electrically connected and controlled in any suitable manner.

In the drawings the heater is shown operatively in its simplest form taking air from the room through the recesses in the grilles, which are always open, and with both the auxiliary register within said room and the register communicating with the exterior of the house in the closed position. During very cold weather it is often desired to accelerate the heating of the room which is accomplished by opening the auxiliary register, which will permit a larger volume 90 of air to be conducted from the room through the heating system. During mild weather, and at times when it is desired to freshen the air within the room, the register communicating with the exterior of the 95 house is opened allowing fresh air to be drawn into said room through the heater. It is obvious that both the auxiliary and the exteriorly communicating registers may be kept open at one and the same time.

From the above description taken in connection with the accompanying drawings the advantages of the construction and of the method of operation of my electric

heater will be readily apparent to those skilled in the art to which the invention relates, but, while I have described the principle of operation of the invention, together with the device which I now consider to be the best embodiment thereof, I desire to have it understood that the heater shown is merely illustrative and that such changes may be made as are within the scope of the following claims.

What I claim is:—

1. An electric heater comprising a housing; a grille for said housing having air intake openings formed therein; a casing centrally disposed within the said housing adapted to form an air heating chamber, said casing associated with said housing forming a conduit for the passage of air to be heated; a container for liquid formed on said casing within said air heating chamber; a downwardly converging heating element disposed within said air heating chamber; a grille for said air heating chamber having air outlet openings formed therein and controlling means for said openings.
2. An electric heater comprising a housing a grille for said housing having air intake openings formed therein; a cylindrical casing centrally disposed and extending downwardly within said housing adapted to form an air heating chamber therein, said casing associated with said housing forming a conduit for the passage of air to be heated; an annular container for water formed on the said casing within the said air heating chamber; a plurality of downwardly converging heating elements concentrically disposed within said air heating chamber; a grille for said air heating chamber having air outlet openings formed therein; and a register for said last named openings for controlling the radiation of heated air from said heating chamber.
3. An electric heater comprising a housing; a grille for said housing having air intake openings formed therein; a cylindrical casing centrally disposed and extending downwardly within said housing adapted to form an air heating chamber therein; said casing associated with said housing forming a conduit for the passage of air on said casing within said air heating chamber; a plurality of downwardly converging heating elements concentrically disposed within said air heating chamber; a grille for said air heating chamber having air outlet openings formed therein; and a register for said last named openings for controlling the radiation of heated air from said heating chamber.
4. An electric heater comprising a housing; a grille for said housing having air intake openings formed therein; a cylindrical casing centrally disposed and extending downwardly within said housing adapted to

form an air heating chamber therein, said casing associated with said housing forming a conduit for the passage of air to be heated, an air conduit adapted to establish communication between the room to be heated and said housing and air heating chamber; an air conduit adapted to establish communication between the exterior of the building and said housing and air heating chamber; a plurality of downwardly converging heating elements concentrically disposed within said air heating chamber; a grille for said air heating chamber having air outlet openings formed therein; and a register for said last named opening for controlling the radiation of heated air from said air heating chambers.

5. An electric heater comprising a housing; a grille for the upper end of said housing having air intake openings formed therein; a cylindrical casing centrally disposed and extending downwardly within said housing adapted to form an air heating chamber therein, said casing associated with said housing forming a conduit for the passage of air to be heated; intercommunicating conduits adapted to establish communication between the room to be heated and said housing and air heating chamber and the exterior of the building and said housing and air heating chamber; registers disposed in said intercommunicating conduits adapted to control the circulation of air therethrough; a downwardly converging heating element concentrically disposed within said air heating chamber comprising an upper annular plate; a concentric annular row of recessed integral bosses formed on the underside of said upper annular plate; a lower annular plate of relatively lesser diameter concentrically disposed below and in spaced apart relation with respect to said upper annular plate; a concentric annular row of recessed integral bosses formed on the upper side of said lower annular plate; a plurality of cores of refractory material disposed in tapering relation having their upper ends disposed in the recessed bosses in said upper annular plate, and their lower ends disposed in the recessed bosses in said lower annular plate; electrical heating coils disposed on said cores; a plurality of tie rods interposed between said coils adapted to secure said upper and lower annular plate as a unit; a grille for said air heating chamber having air outlet openings formed therein; means to secure said heating element to the underside of said grille; and a register for said air outlet openings for controlling the radiation of heated air from said air heating chamber.

In witness whereof, I hereunto subscribe my name this 16th day of August, A. D. 1920.

ANDREW J. HOLMES,
